TABLE

Dennis L. Jenkins, 4449 Ponce de Leon Blvd.,
Coral Gables, Fla. 33146

Filed Dec. 31, 1970, Ser. No. 26,725

Term of patent 14 years

Int. Cl. D6—03

U.S. Cl. D6—146

FIG. 2

FIG. 1

FIG. 4

FIG. 1 is a perspective view of a table showing my design;

FIG. 2 is an elevational view showing one of the four identical sides;

FIG. 3 is a modified form of the table of FIG. 1 wherein the article is round rather than square; and

FIG. 4 is a view in side elevational view thereof.

I claim:

The ornamental design for a table, as shown and described.
